UNITED STATES PATENT OFFICE.

FORREST EDWARD BEEN, OF MAGRATH, ALBERTA, CANADA.

RURAL-MAIL DELIVERING AND COLLECTING SYSTEM.

No. 921,504.

Specification of Letters Patent.

Patented May 11, 1909.

Application filed August 8, 1908. Serial No. 447,638.

To all whom it may concern:

Be it known that I, FORREST EDWARD BEEN, of Magrath, in the Province of Alberta, Canada, have invented certain new

and useful Improvements in Rural-Mail Delivering and Collecting Systems, of which the following is a specification.

My invention relates to improvements in rural mail delivery systems, and the objects 10 of my invention are to provide means for delivering and collecting mail from a number of isolated rural stations, and such means as will enable a continuous service to be automatically effected without manual 15 attention.

In its construction, the invention includes a suspended track on which an electrically-operated carrier is mounted, in combination with stations and means coöperative between 20 the carrier and the stations for discharging and receiving a mail box at each station, all as hereinafter more fully set forth and described in the accompanying specification and drawings.

25 In the drawings,—Figure 1 is a perspective view showing the track with the carrier mounted thereon. Fig. 2 is a longitudinal section through the carrier. Fig. 3 is a perspective view through the front of the same. Fig. 4 is a section through one of the mail 30 boxes. Fig. 5 is a perspective view of one of the mail boxes. Fig. 6 is a sectional detail of the opening of the chamber in the carrier, adapted to receive the mail boxes. Fig. 7 35 is a transverse section on the line 2—2, Fig. 6. Fig. 8 is a section through one of the receiving projections on one of the stations.

Referring to the drawings, A and B are the two tracks preferably in the form of 40 wires, supported by brackets 10 and 11 from posts C.

D represents the carrier mounted on the track, the upper wheels 12 and 13 of which are supported by brackets 14 and 15, and the 45 lower wheels 16 and 17 being supported from brackets 18 and 19 which extend in casings 20 and 21, and are pressed downwardly by springs 22 and 23, thereby resiliently holding the wheels in contact with the 50 track. The carrier is driven by a suitable electric motor E located therein, and connected by suitable pulleys and belting with

the wheels 14 and 15, the power for the motor being transmitted through tracks A and B in the usual manner for electrically-operated systems.

The carrier D is formed on the interior with a plurality of longitudinally-extending and rearwardly-opening chambers F, F, within which the mail boxes G, to be delivered, are contained. Each of these mail containing boxes is rectangular in cross-section, and is provided at each end with outwardly protruding spring-actuating dogs 24, those in the embodiment illustrated being 65 formed of hollow sheet metal, and extending through an aperture in the end of the mail box, having flanges 25 abutting the inside of the mail box and being actuated outwardly by a suitable spring 26. The width 70 of the longitudinal chambers within which the boxes are contained is such that the dogs will be pressed inwardly in said chambers. The outside of the casing is provided on each side with notches 27 at the outlet of 75 each of the chambers whereby when the box comes near the end the dogs 24 thereon will spring outwardly and remain in position ready to be engaged by the engaging means on the station, as hereinafter described. The mail boxes are normally 80 pressed toward the ends of the chambers F by means of springs H within the chamber and the outermost box is prevented from passing out of the chamber by spring metal 85 dogs 28 and 29, which extend over the slots 27 in the chamber and thus normally prevent the mail boxes from passing out of the chamber, but which yield when the dogs are engaged at the station to permit the 90 box to be moved out.

To receive the mail boxes from the different stations, a plurality of forwardly opening longitudinally extending chambers I, I, are provided, these chambers having a 95 plurality of pivoted dogs 30 near the mouth thereof, adapted to prevent the boxes from passing out after they have once entered. This is accomplished by providing a plate 31 below the pivoting points of the dogs 100 having slots 32 therein, through which the dogs extend, one edge of the slot being adapted to bear against the side of the dog when the dog is in vertical position, shown

in Figs. 6 and 7. The chambers are provided on the sides with slots 50 through which the dogs 24 on the boxes may extend, the said slots ending shortly before the end 5 of the side, whereby the box will be retained within the carrier.

J represents one of the delivering and receiving stations comprising a post 33 having a rectangular frame 34 on top thereof, which extends around the tracks A and B. To steady the carrier as it approaches a station, a brace 35 extends from the post upwardly and thence along the under track and other braces 36 and 37 extend through 15 the side of the frame 34, and are adapted to steady the sides of the carrier. On the sides of the frames 34, two spring arms 38 and 39 are provided, having inwardly turned ends adapted to engage the outwardly-projecting dogs 24 on the boxes, in one of the chambers F, while other projections 40 and 41 are provided between which the mail box to be collected by the carrier is held in readiness by the spring dogs. 25 In operation of the system, the mail boxes are arranged in the carrier in the order in which the stations occur, and the projections 38 and 39 are arranged at different heights on different stations, in such a manner that the mail will be discharged from the different compartments F in the proper order. When the carrier passes a station, one of the mail boxes will be engaged by the projections 38 and 39 and withdrawn 30 from the chamber F, and will then fall to the ground or into a suitable receptacle to be afterward collected by the proper recipient. At the same time the mail box supported between the projections 40 and 41 35 will enter into one of the chambers I and be carried along with the carrier. The power being supplied by the tracks A and B, the carrier will pass through all the stations without stopping, delivering and receiving mail from each. 40

As many changes could be made in the above construction, and many apparently widely different embodiments of my invention could be made without departing from the spirit or scope thereof, it is intended that all matter contained in these specifications and drawings shall be interpreted as 50 illustrative and not in a limiting sense. It is also to be understood that the language of the following claims is intended to cover such generic and specific features of the invention herein described, which, as a matter of language, might be said to be included 55 thereby.

60 What I claim as my invention is:—

1. A mail delivering system including tracks, stations at intervals thereon, a self-propelling carrier mounted on the tracks having a longitudinally-extending, rear-

wardly-opening compartment therein, a plurality of mail boxes in the compartment having spring dogs thereon adapted to be forced outwardly, but normally retained in innermost position by the sides of the compartment, the said compartment having 65 slots at the sides thereof near the end, whereby the dogs on the outermost section may be sprung outwardly, means for pressing the mail box to outermost position, releasable means for preventing the outermost 70 box from falling out and means on the station for engaging the dogs on the outermost 75 box.

2. A mail delivering system including 80 tracks, stations at intervals thereon, including frames, a mail box having outwardly protruding dogs adapted to engage the side of the frame, a self-propelling carrier mounted on the tracks having a forwardly-opening compartment therein, adapted to 85 collect the mail box supported from the frame, and pivoted dogs in the front of the compartment preventing the box passing out of the same.

3. A mail delivering system including 90 tracks, stations at intervals thereon comprising frames extending around the tracks and having inwardly-extending projections, a mail box having outwardly actuated dogs adapted to engage the projections, a self-propelling carrier mounted on the tracks having a forwardly opening compartment 95 adapted to collect the mail box from between the projections.

4. A mail delivering system, including 100 tracks, stations thereon comprising rectangular frames extending about the tracks, braces on the stations supporting the underside of the tracks, a self-propelling carrier mounted on the tracks, and means on each 105 station, co-operative with the carrier, for delivering a mail box thereto and receiving a mail box therefrom.

5. A mail delivering system, including 110 tracks, stations at intervals thereon, comprising frames extending about the tracks, a carrier, braces on the frames adapted to support the sides of the carrier as it passes between the stations, and means at each station for delivering a mail box to the carrier 115 and for withdrawing one therefrom.

6. A mail delivering system, including 120 tracks, stations at intervals thereon, including frames extending around the tracks, a mail box having outwardly-actuated spring dogs adapted to engage the frames, self-propelling carriers mounted on the tracks having a forwardly opening compartment adapted to collect the mail box from the frame.

7. A mail delivering system, including 125 tracks, stations thereon, a self-propelling carrier having a rearwardly opening com-

partment-boxes in said compartments having outwardly, spring-actuated dogs therein, the said compartment having means permitting the extension of the dogs of the mail box at a determined point and means in the station adapted to engage the dogs on the box.

In witness whereof I have hereunto set my hand in the presence of two witnesses.

FORREST EDWARD BEEN.
